J. L. STENGEL

BELT PUNCH PLIERS

Filed April 23, 1923

INVENTOR:

Joseph L. Stengel
BY
Walter A. Knight
ATTORNEY.

UNITED STATES PATENT OFFICE.

JOSEPH L. STENGEL, OF CINCINNATI, OHIO.

BELT PUNCH PLIERS.

Application filed April 23, 1923. Serial No. 634,016.

To all whom it may concern:

Be it known that I, JOSEPH L. STENGEL, a citizen of the United States, residing at Cincinnati, in the county of Hamilton and State of Ohio, have invented new and useful Improvements in Belt Punch Pliers, of which the following is a specification.

My invention relates to belt punch pliers or tools used when coupling the ends of round leather belting. The particular object of this type of plier is to square off the end of a piece of belting and pierce a hole near the end thereof in such a manner that two squared ends of belting can be neatly and readily secured together by means of a wire coupling.

Various types of pliers have been constructed to attain this object, but heretofore great difficulty has been experienced in constructing a tool that would punch or pierce a hole in the center of the squared end at every operation, and it will readily be seen that if the belting is punched anywhere but in the center of the end, the joint will be materially weakened thereby.

The principal object of my invention is to construct a handy, compact and efficient belt punch plier that can be relied upon at all times to punch or pierce a hole in the center of the belting, and to attain this object I construct my belt punch plier in such a manner that the belting to be punched will be firmly gripped within the jaws of the pliers before attempting to pierce a hole in the belting.

In the particular embodiment of my invention selected for illustration:

Fig. 1 is a side elevation of a common type pair of pliers embodying my invention, the jaws of the pliers shown open, ready to receive a piece of belting.

Fig. 2 is a longitudinal sectional view indicating the position of the jaws of the pliers when gripping a piece of belting and prior to punching a hole therein,

Fig. 3 is a side elevation of my complete device showing the final position of the lever D, and punch E, after the belting has been squared and punched, the belting not being shown,

Fig. 4 is a detail showing the cutter C and extension c¹,

Fig. 5 is a fragmentary top plan view showing the slot d and method of securing the piercing means therein, and

Fig. 6 is a detail showing the preferred form of piercing member.

Referring now particularly to Fig. 1. A pair of handle levers A and B are crossed and fulcrumed at c⁵ the extended portion a of the lever A is secured to the upper jaw a² by the rivet a¹ and the extended portion b of the lever B is secured to the lower jaw b² by the rivet b¹ thereby forming a pair of pliers.

In order to maintain the jaws a² and b² in parallel relation to each other when the pliers are in either open or shut position said jaws are provided with longitudinal slots a³ and b³, in which slide the studs a⁴ and b⁴, secured to the handle levers A and B respectively.

A cutter C is secured to one side of the upper jaw a² by screws c and is extended at c¹ so as to coact with a supporting bracket strip c², on the opposite side of said jaw, in forming a bracket to which is secured the piercing lever D, by means of the stud d. A punch or piercing member E, constructed with circumferential beads e and e¹ at the upper end thereof is loosely secured within a slot d² formed in the piercing lever D, and prevented from displacement therefrom by means of said beads. The lower cutting portion of said piercing member is adapted to operate thru the hole a⁵ in the upper jaw a², said hole opening into the jaw of the pliers in the center of the angular cut away portion a⁶. The lower jaw b² is provided with a corresponding angular cut away b⁶ and hole b⁵ which coact with said upper jaw in holding and punching the leather belting.

A spring d¹ is secured between the upper side of the upper jaw a² and the under side of the piercing lever D to hold said lever in position and to assist the piercing lever to return to its normal position as shown in Fig. 1, after having punched a hole as indicated in Fig. 3.

The operation of my invention is as follows:

The leather belting is inserted between the jaws a² and b² preferably resting in the angular cut away portion b⁶, the handle members A and B are then gripped together thereby squaring the end of the belting by means of the cutter C and securely gripping the belting between the cut away portions a⁶ and b⁶ in the jaws a² and b². The piercing lever D is then gripped or pressed to-

ward the handle B, thereby carrying the punch or piercing member E thru the center of the belting. On releasing the lever D the spring d¹ operates to assist in disengaging 5 the punch from the belting.

In the particular embodiment of my invention, selected for illustration, I have shown angular cut away portions on each jaw, which combine to make a diamond 10 shape opening when the jaws are closed, it will be seen that this construction enables me to hold the belting at all times firmly and in alignment with the piercing means.

My improved piercing means is preferably constructed, dagger shaped or oval in cross section, the lower end being gradually tapered to a point, so as to pierce an oval hole in the belting rather than punch a 15 round hole therein.

I do not wish to be limited to the exact construction as shown but claim within the scope of my invention all modifications readable on the claims that will be finally allowed.

I claim as my invention and desire to secure by Letters Patent of the United States:

1. In combination with a pair of pliers, a

lever fulcrumed to said pliers and punching means carried by said lever adapted to operate thru the jaws of said pliers.

30

2. In a belt punching instrument comprising a pair of pliers provided with a belt receiving recess in the jaws thereof, a lever secured to one of said jaws, punching means carried by said lever, and a hole thru one 35 of said jaws opening into said recess and adapted to receive said punching means.

3. In a belt punching instrument comprising a pair of pliers provided with a belt receiving recess in the jaws thereof, a lever 40 fulcrumed to one of said jaws, a slot in said lever, and a punch loosely secured within said slot, adapted to operate thru said jaws.

4. In a belt punching instrument comprising a pair of pliers provided with a belt 45 receiving recess in the jaws thereof, a lever fulcrumed to one of said jaws, punching means carried by said lever, means for automatically releasing said punching means and said lever on the completion of the 50 punching operation.

In testimony whereof I have hereunto set my hand.

JOSEPH L. STENGEL.
